UNITED STATES PATENT OFFICE

2,452,062

ELECTRICAL DISCHARGE TUBE

James D. Le Van, Belmont, Mass., assignor to Raytheon Manufacturing Company, Newton, Mass., a corporation of Delaware

Application July 29, 1943, Serial No. 496,563

7 Claims. (Cl. 250—27.5)

1

This invention relates to ultra high frequency velocity-modulated tubes, and more particularly to such tubes in which a stream of electrons is subjected to bunching and debunching effects by passing successively through a pair of control electrodes.

In devices of the foregoing nature, the spacing between the control electrodes must be accurately related to the frequency for which the device is intended and to the voltages impressed on the device which affect the speed of the electrons passing through the control electrodes, so that the transit time of the electrons passing from one control electrode to the other bears a definite relation with respect to the period of the oscillations produced by the device. Unless this spacing is maintained constant, the frequency at which the device operates tends to shift or the device drops out of adjustment and fails to operate properly. In many devices of this kind it has been found that during operation changes occurred which required a continuous external control of the voltages and the external circuit constants supplied to the tube in order to keep it operating at the proper frequency and at the proper level of intensity. I have found that such changes have been due in considerable measure to temperature changes within the tube itself which introduced variations in the spacing between the pair of control electrodes.

An object of this invention is substantially to eliminate the effect of temperature on the frequency and intensity of response of an ultra high frequency velocity-modulated tube of the foregoing type.

Another object is to produce a spacing between a pair of electron bunching or debunching electrodes in such a tube which is substantially independent of temperature.

The foregoing and other objects of this invention will be best understood from the following description of exemplifications thereof, reference being had to the accompanying drawing, wherein:

Fig. 1 is a longitudinal cross-section through an ultra high frequency velocity-modulated tube embodying my invention;

Figs. 2 and 3 are diagrams illustrating certain geometrical principles involved in two forms of my invention; and

Fig. 4 is a set of curves illustrating the degree 50 ating grid 4.

2

of temperature compensation which may be obtained in certain embodiments of my invention.

The tube illustrated in the drawing consists of an evacuated envelope 1 of some suitable material, such as glass, containing the cathode structure 2, a reflecting electrode 3, an accelerating grid 4 adjacent the cathode, and a pair of control electrode elements 5 and 6 interposed between the accelerating grid and the reflecting electrode 3.

The cathode is of the hollow indirectly-heated type having a flat upper active surface, preferably coated with an electron-emissive material 7 which may consist of the usual mixture of barium and strontium oxides. Surrounding the hollow cathode is a focusing shield or ring 9 which tends to focus the electrons coming from the coating 7 into compact beam. Surrounding the focusing ring 9 is an accelerating grid-supporting cylinder 10 having an opening at the upper end thereof across which is supported a perforated grid member 11 consisting of fine conducting wires so as to interpose a minimum of grid surface for intercepting the electrons contained in the electron beam. A cathode lead-in wire 12 is sealed through a press 13 formed on the upper end of a reentrant stem 14 contained within the envelope 1. The lead-in 12 is electrically connected to the cathode 2, thus providing an external electrical connection to the cathode. A pair of heater leads 15 is likewise sealed through the press 13 and is electrically connected to the ends of the heater member 8. A pair of supporting standards 16 is likewise sealed in the press 13, and serves to support the electrode assembly associated with the reentrant stem 14. Both of these standards 16 may be electrically connected to the lower edge of the member 10 which clamps cooperating projections on the associated electrode members between a pair of insulating washers 17, thus spacing the members in proper relationship with respect to each other and maintaining these members firmly in position with respect to the reentrant stem 14. The focusing ring 9 may be welded to the lower end of the cathode 2, and thus be electrically connected to and supported by the cathode. One of the standards 16 may continue through the press 13 so as to provide an external electrical connection to the accelerating grid 4.

The structure described above produces a compact beam of electrons which emerges through the perforated member 11 with the requisite velocity. This electron beam is subjected to the action of the pair of control grids 5 and 6. The structure of the control grid 5 is formed by a lead-in ring 18 which is sealed through the side walls of the envelope 1, the portions of envelope 1 above and below ring 18 providing separate rigid supporting elements for said ring. The internal edges of the ring 18 are turned upwardly and form a relatively elongated cylindrical member 19 which has an opening at its upper end across which a perforated conducting member 20 is supported. Here likewise the perforated member 20 is made of fine conducting wires for the same reasons as specified in connection with member 11. The second control grid structure 6 is formed of a conducting ring 21 sealed through the side walls of the envelope 1, the portions of envelope 1 above and below ring 21 providing separate rigid supporting elements for said ring. The inner ends of the ring 21 are turned downwardly so as to form a relatively short cylindrical member 22 having an opening at the lower end thereof across which is supported a perforated member 23 likewise formed of fine conducting wires.

The reflecting electrode 3 is supported by an anode lead-in conductor 24 sealed through a re-entrant stem 25 formed in the upper end of the envelope 1. A getter assembly 26 may be conveniently supported on the lead 24. Of course it is to be understood that the construction as described above is assembled and evacuated in accordance with standard vacuum tube practice, so as to produce a high vacuum within the envelope 1, and to activate the coating 7, so as to provide for copious thermionic emission therefrom.

The outer edges of the rings 18 and 21 form external connections to the grids 5 and 6. In order for the tube, as described above, to generate ultra high frequency oscillations, a hollow resonant chamber 27, which may be conveniently in the form of a toroid open along its inner edge, is fastened with its upper and lower edges respectively to the rings 21 and 18. The resonant chamber member 27 is preferably formed of a highly conductive material, such as copper. The oscillations which are produced by the device may be picked up by a coupling loop 28 placed within the chamber 27 and led off by a conductor 29 which conveniently may be surrounded by a pipe 30 fastened into the chamber 27 so as to form with the conductor 29 a concentric line.

When the tube is energized with the proper potentials, a beam of electrons coming from the cathode 7 is accelerated by the grid 11, and passes through the grid structures 5 and 6. As the beam emerges from the grid structure 6, it is reflected by the reflecting electrode 3 back through the pair of control grids. As the reflected beam emerges from the grid 5, it is reflected by the structure below it so that it again passes through the grid members 5 and 6 to finally fall upon the outer surface of the ring 21 or upon the reflecting electrode 3 with relatively low velocities. As is well known, the initial passage of the beam through the grids 5 and 6 produces a bunching action, and upon reflection and repassage of the beam through these control electrodes, a de-bunching action is produced which feeds ultra high frequency energy to the resonant circuit formed by the hollow resonant chamber 27, thus setting up ultra high frequency oscillations which may be led off from the concentric line 29, 30.

In prior tubes of this kind it was recognized that it was desirable for various members of the tube, particularly the grid structures 5 and 6 which carry substantial amounts of ultra high frequency energy, to be made of highly conductive material, such as copper, in order to make for highly efficient devices. As already stated, such prior devices during operation underwent various changes which necessitated changes in the voltages and circuit constants applied to the tube in order to keep it operating properly. I have found that these changes were due to variations in temperature within the tube. These variations in temperature, particularly at the cylinder 19 and its associated supporting structure produced small variations in the dimensions of these elements which resulted in a greatly amplified movement of the upper end of the cylinder 19 with respect to the member 6. I have found that it was the resultant change in the spacing between the perforated members 20 and 23 which produced the difficulties encountered in the prior art.

I have discovered that if the portion 31 of the ring 18 between the cylinder 19 and the inner walls of the envelope 1 is bent so as to form an angle between the side walls of the cylinder 19 and the portion 31 and said angle differs substantially from 90°, the difficulties heretofore encountered are substantially eliminated. The manner in which this is accomplished will be made clearer by referring to Fig. 2, which is a geometrical representation of one-half of the grid structure 5 within the walls of the envelope 1. In Fig. 2, R represents the radius of the cylinder 19; L represents the length of said cylinder; A is the distance between the side wall of the cylinder 19 and the inner side walls of the envelope 1; B is the length of the ring 18 between the side walls of the cylinder 19 and the inner walls of the envelope 1; and Y is the vertical distance between the outer end of B and the lower end of the cylinder 19. The upper end of the cylinder 19 is represented by P and the lower end by Q. The angle between B and the side wall of the cylinder 19 is designated as θ . The arrangement, as shown in Fig. 2, may represent the conditions which exist in the tube at the cold or room temperature.

As the tube is put in operation, the energy liberated by such operation heats up the grid structure, diagrammatically shown in Fig. 2, and all parts thereof are subjected to a certain degree of expansion dependent upon its coefficient of expansion and the temperature rise. For any given structure we can calculate the extent of movement which results from such expansion. For purposes of analysis we will assume that all parts of the grid structure are of the same material and are subjected to the same temperature rise.

It will be seen that

$$Y = A \cot \theta \quad (\text{Equation 1})$$

As the temperature of the structure increases by a temperature t , Y increases to Y_1 .

$Y_1 = \sqrt{(B + B\alpha t)^2 - (A - R\alpha t)^2} \quad (\text{Equation 2})$
where α is the temperature coefficient of expansion of the grid material. Usually this is copper, in which case α is about 17.8×10^{-6} . The change in the distance Y can be represented by ΔY .

$$\Delta Y = Y_1 - Y \quad (\text{Equation 3})$$

We see also that

$$B = A \operatorname{cosec} \theta \quad (\text{Equation 4})$$

and thus

$$\Delta Y = \sqrt{(A \operatorname{cosec} \theta + A \operatorname{cosec} \theta \alpha t)^2 - (A - R \alpha t)^2} - A \cot \theta \quad (\text{Equation 5})$$

From Equation 5 we can calculate ΔY , which thus represents the distance by which the point Q moves upon an increase in temperature. With θ an acute angle, this motion will be downward. We also see that the amount of this motion is dependent only upon A, R, α , t, and θ .

While the above is taking place, L also expands by an amount ΔL , where

$$\Delta L = L \alpha t \quad (\text{Equation 6})$$

The expansion of L tends to move the point P upward, and thus the net vertical motion of the point P will be

$$\Delta P = \Delta Y - \Delta L \quad (\text{Equation 7})$$

In Fig. 4 I have applied the above method of calculations to a particular embodiment of my novel tube in which A is .1", R is .22", L is .27", α is 17.8×10^{-6} and $t = 300^\circ \text{C}$. In Fig. 4 the solid line curve represents the values of ΔY plotted against variations in the angle θ , derived from such calculations. ΔL is constant and is also represented in Fig. 4. From Fig. 4 we see that if we make θ equal to 90° , as was previously done, the lower end Q of the grid structure will move about thirteen times as much as the expansion in L. We see also that L being the longest linear dimension has a greater linear expansion than either R or B. As θ decreases, the value of ΔY falls off very rapidly, reaches a minimum value at about 30° , and then rises rapidly. The curve of ΔY asymptotically approaches the 0° line. With the particular values selected for Fig. 4, exact compensation for temperature expansion cannot be secured. However, substantial compensation is secured for all values at which θ becomes appreciably acute. For example, the compensation attained at values of θ between about 70° and 7° is sufficient to produce satisfactory operation for many purposes.

The value of θ at which the maximum compensation is secured will vary with different relative values of A, R, L, t and α . At some values for the foregoing quantities, ΔY exactly equals ΔL , and thus exact compensation for temperature variations can be secured. In each instance, however, the value of θ must be a substantially acute angle to obtain the benefits of temperature expansion compensation.

In some applications of my invention the angle which the portion 31 of ring 18 makes with the side walls of the cylinder 19 may be an obtuse angle. Such an arrangement is illustrated diagrammatically in Fig. 3 in which the same reference letters are applied as in Fig. 2. In Fig. 3 it will be seen that the element B makes an obtuse angle λ with the side wall P—Q of the grid cylinder. In Fig. 3 the angle θ is represented between the line B and an extension of the line P—Q. The value of θ is, of course, $180^\circ - \lambda$. Exactly the same analysis as was applied above in connection with Fig. 2 can be applied to Fig. 3 in so far as deriving values of ΔY are concerned. The only difference is that in Fig. 3 ΔP equals the sum of ΔY and ΔL instead of the difference of these quantities as in Fig. 2. However, from Fig. 4 we see that in the particular example therein illustrated, the sum of ΔL and ΔY in the vicinity of the minimum value of ΔY is much less than the difference between ΔY and ΔL at 90° . Thus even with the use of the obtuse angle arrangement of Fig. 3,

the net motion of the point P can be made substantially less than with the prior 90° arrangement. However, in Fig. 3 the net motion of the point P is upward, whereas in Fig. 2 the net motion of the point P is downward with the values as given in connection with Fig. 4. In some instances a motion of the point P downwardly introduces less disturbances in the system than an upward motion.

The analyses as given above assume an ideal condition in which all of the parts are subjected to a uniform temperature increase. In actual practice the conditions may be substantially different in that the temperature of the cylinder 19 may be substantially higher than the temperature of the portion 31 of the ring 18. If we assume that portion 31 remains at a constant temperature while the cylinder 19 increases in temperature, we can again apply Equation 5 to determine the changes which occur. In this case the factor A cosec $\theta \alpha t$ in Equation 5 is always zero. The results of such an analysis are plotted by the dotted curve in Fig. 4. In a practical case the larger values of θ are used since such a structure is easier to manufacture, and also at very small values of θ , B becomes impractically large. At the larger values of θ it will be seen that the predominating factor in producing the motion of point P is the expansion of the radius R of the cylinder 19. From the dotted curve of Fig. 4 it will be seen that with the conditions assumed in connection therewith, exact compensation is obtained at an angle of about 50° , at which point ΔP is zero. The actual operation of the tube probably lies somewhere between the solid and dotted curves of Fig. 4. From this we see that for all acute angle values, for the angle between the portion 31 and the side walls of the cylinder 19, which are substantially different from 90° , excellent temperature compensation is secured. As already pointed out, even with obtuse values of this angle, the temperature compensation may be sufficient for many purposes.

Of course it is to be understood that this invention is not limited to the particular details as described above as many equivalents will suggest themselves to those skilled in the art. For example, other types of ultra high frequency velocity modulated tubes may have my invention utilized therein, such as a tube which contains a separate bunching and a separate debunching pair of grid electrodes. My invention may also be applied to electrode supports in other types of tubes. Various other modifications and adaptations of my invention will readily suggest themselves to those skilled in the art. It is accordingly desired that the appended claims be given a broad interpretation commensurate with the scope of the invention within the art.

60 What is claimed is:

1. An electrical space discharge tube comprising a plurality of electrodes, a first of said electrodes being supported with respect to an adjacent electrode to provide a linear electron path between said electrodes, said first electrode being supported between rigid supporting elements by supporting means of substantial length, said first electrode having a portion extending from said supporting means along the direction of said electron path, the length of said portion being substantially greater than the shortest distance between said portion and said supporting elements, said portion having a substantial thermal coefficient of expansion whereby variations in the temperature of said electrode will tend to produce

substantial variations in the length of said electron path, said supporting means likewise having a substantial thermal coefficient of expansion and forming an angle with the direction of said electron path, said angle being of a substantial value substantially different from ninety degrees.

2. An electrical space discharge tube comprising a plurality of electrodes, a first of said electrodes being supported with respect to an adjacent electrode to provide a linear electron path between said electrodes, said first electrode being supported between rigid supporting elements by supporting means of substantial length, said first electrode having a portion extending from said supporting means along the direction of said electron path, the length of said portion being substantially greater than the shortest distance between said portion and said supporting elements, said portion having a substantial thermal coefficient of expansion whereby variations in the temperature of said electrode will tend to produce substantial variations in the length of said electron path, said supporting means likewise having a substantial thermal coefficient of expansion and forming an angle with the direction of said electron path, said angle being of a substantial acute value substantially different from ninety degrees.

3. An electrical space discharge tube comprising a plurality of electrodes, a first of said electrodes being supported with respect to an adjacent electrode to provide a linear electron path between said electrodes, said first electrode being supported between rigid supporting elements by supporting means of substantial length, said first electrode having a portion extending from said supporting means along the direction of said electron path, the length of said portion being substantially greater than the shortest distance between said portion and said supporting elements, said portion having a substantial thermal coefficient of expansion whereby variations in the temperature of said electrode will tend to produce substantial variations in the length of said electron path, said supporting means likewise having a substantial thermal coefficient of expansion and forming an angle with the direction of said electron path, said angle being of a substantial obtuse value substantially different from ninety degrees.

4. An electrical space discharge tube comprising a plurality of electrodes, a first of said electrodes being supported with respect to an adjacent electrode to provide a linear electron path between said electrodes, one of said electrodes being a grid member extending substantially transverse to said electron path supported by a substantial length of a metallic supporting member substantially at right angles to said grid member and substantially in line with said electron path, said supporting member being in turn supported between rigid supporting elements by supporting means of substantial length extending transversely of said electron path, the length of said supporting member being substantially greater than the shortest distance between said supporting member and said supporting elements, said supporting means and supporting member having substantial temperature coefficients of expansion, said supporting means forming a substantial angle substantially different from ninety degrees with said supporting member.

5. A high frequency tube comprising an envelope containing an electron-emissive cathode, means in said envelope for accelerating a beam of electrons from said cathode, a pair of control grids mounted in the path of said beam, and an

additional electrode, said pair of control grids being adapted to be connected to a resonant circuit to impart velocity modulation to the electrons in said beam, one of said grids being spaced from the other of said grids and being supported by a substantial length of supporting member extending in the direction of said beam, said supporting member being in turn supported between rigid supporting elements by supporting means of substantial length extending transversely of said beam, the length of said supporting member being substantially greater than the shortest distance between said supporting member and said supporting elements, said supporting means having a substantial temperature coefficient of expansion, said supporting means forming a substantial angle substantially different from ninety degrees with said supporting member whereby variations in the length of said supporting means produce variations in the angular relation between said supporting means and said electron path which produce a change in the position of said one grid along the direction of said beam which is substantially smaller than the change which would be produced if said angle were substantially ninety degrees.

6. A high frequency tube comprising an envelope containing an electron-emissive cathode, means in said envelope for accelerating a beam of electrons from said cathode, a pair of control grids mounted in the path of said beam, and an additional electrode, said pair of control grids being adapted to be connected to a resonant circuit to impart velocity modulation to the electrons in said beam, one of said grids being mounted at one end of a tubular supporting member, said tubular member having its axis extending in the direction of said beam, said last-named grid and its supporting member being supported within a tubular portion of said envelope by an annular member of a substantial length interconnecting the other end of said tubular member and the inner wall of said tubular portion and extending substantially transverse to the direction of said beam, the length of said tubular member being substantially greater than the shortest distance between said tubular member and said tubular portion, said annular member having a substantial temperature coefficient of expansion, said annular member forming a substantial angle substantially different from ninety degrees with the side walls of said tubular member whereby variations in the length of said annular member produce variations in the angular relation between said annular member and said electron path which produce a change in the position of said one grid along the direction of said beam which is substantially smaller than the change which would be produced if said angle were substantially ninety degrees.

7. An electrical short wave generator tube comprising an hermetically sealed glass envelope, a pair of electrodes in said envelope for supporting an electron flow therebetween, a pair of annular metal plates between said electrodes, spaced therefrom and extending through the wall of said envelope and having spaced, aligned, lipped openings through which said electron flow may pass within said envelope, at least one of said plates having a concentric annular depression therein within the envelope and between said envelope and the inner edge of said annular plate to counteract the movement of its lipped opening under heat variation, a grid in each of said openings,

9

and an electrical connection between said plates and outside said envelope.

Certificate of Correction

Patent No. 2,452,062.

October 26, 1948.

JAMES D. LE VAN

It is hereby certified that error appears in the printed specification of the above numbered patent requiring correction as follows:

Column 5, line 2, Equation 5, for

$$\Delta Y = \sqrt{(A \operatorname{cosec} \theta + A \operatorname{cosec} \theta \alpha t)^2 - (A - R \alpha t)^2 - A \cot \theta}$$

read

$$\Delta Y = \sqrt{(A \operatorname{cosec} \theta + A \operatorname{cosec} \theta \alpha t)^2 - (A - R \alpha t)^2 - A \cot \theta}$$

and that the said Letters Patent should be read with this correction therein that the same may conform to the record of the case in the Patent Office.

Signed and sealed this 15th day of February, A. D. 1949.
